RADIO RECEIVER

Yves Rocard, Paris, France, assignor to Compagnie Generale de Telegraphie Sans Fil, a corporation of France

Application September 29, 1932, Serial No. 635,370
In France January 30, 1932

9 Claims. (Cl. 250—20)

This application is based on and corresponds to French Patent No. 745,631, granted February 21, 1933. The present invention relates to improvements in radio receivers, and especially to frequency-changing devices.

The present invention discloses a general principle, and improved methods, adapted to insure in the proper manner a change in frequency particularly by the aid of a radio modulator twin-grid tube without creating, or permitting the production of, stray waves whose interference with the wave of the new frequency, or with the component or constituent waves, would result in inconvenience that would manifest itself at the acoustic output end of the equipment in the form of fundamental noises, whistling, etc. Its chief application is in connection with the superheterodyne type of radio receiver set.

The efficiency of the methods here disclosed may be explained by, and is based upon, an observation made by the inventor according to which the curvature of the characteristic of the tubes which, in one stage of amplification, as is well known in the art, results in diaphony (or cross-talk), and an apparent growth in the depth of the modulation, will also cause, inside a tube intended and designed to insure a change in frequency, waves having a frequency close to that of the new frequency which is desired to be obtained; and these waves on passing into the succeeding amplifier produce upon final detection a heat of a relatively low and audible frequency.

Taking the case of a tube whose plate current i developed as a function of the voltage at the grid V_g is expressed by

$$(1) \quad i = aV_g + bV_g^2 + cV_g^3 + dV_g^4 + eV_g^5 + fV_g^6 + \dots$$

and assuming that the grid potential is due to a certain number of signals

$$(2) \quad V_g = \alpha \sin \omega t + \beta \sin \omega' t + \gamma \sin \omega'' t + \dots$$

among which is contained the desired signal ω , a heterodyne signal intended to enter into beat relations with the former in order to bring about a change of frequency, and a certain number of confused or indeterminate ones, by developing Equation (1) of i in the light of Equation (2) for V_g , and transforming the terms so as to bring out the purely sinusoidal terms, there will finally be found in i a very large number of sinusoidal components of different frequencies.

Taking as a practical instance the case of the Daventry station received while the Radio-Paris and the Eiffel Tower stations are in operation, if D designates the frequency of the Daventry sta-

tion (D=193,000 cycles), P that of the Radio-Paris station (174,000 cycles), and F that of the Eiffel Tower station (207,000 cycles), among the beat waves that will arise the following frequencies may be noted:

Nature of beat	Amplitude proportional to:	Frequency value	
2D—P—F	d	5,000	5
3D—2F—P	f	9,000	
D—F—	b	14,000	
D—P—	b	19,000	
3D—2P—F	f	24,000	
2D—2F—	d	28,000	
F—P—	b	33,000	
2D—2P—	d	38,000	10
3D—3F—	f	42,000	
2F—P—D—	d	45,000	
2P—F—D—	d	52,000	
3D—3P—	f	57,000	
3F—2D—P—	f	61,000	
2F—2P—	d	66,000	
3P—2D—F—	f	71,000	
3F—2P—D—	f	80,000	20
3P—2F—D—	f	85,000	
3F—3P—	f	99,000	

The amplitude of a beat, on the other hand, is proportional to the field of all of the transmitters causative of beats or interfering actions, each thereof with an exponent equal to the coefficient of its frequency. For instance, the beat 3F—2P—D at 80,000 cycles is proportional to the cube of the field of the Eiffel Tower times the square of the Radio-Paris field times the Daventry field. Whence the result that this beat will be proportional to the sixth power of the effective height of the antenna or aerial, all other things, of course, being equal.

If it is desired to receive Daventry by a superheterodyne set located close to the Radio-Paris or the Eiffel Tower broadcasting stations, all of the waves hereinbefore enumerated will arise, and there will occur furthermore beats of the waves of the three sending stations with the heterodyne wave, a fact that should also be taken into consideration. Suppose that 60,000 cycles per second is the value of the mean frequency. In the amplification of the mean frequency adjusted to 60,000 cycles, with a certain band pass, the beat 3F—2D—P just as the beat 3D—3P will pass, and as a result of subsequent interference between them and with the mean frequency wave of 60,000, whistling notes of 1,000, 3,000 and 4,000 periods will be produced in the detector. If the carrier-wave of the Eiffel Tower station is stopped, the whistles of 1,000 and 4,000 periods will disappear, and if Radio-Paris in turn stops also the 3,000 periods whistle will vanish.

The importance and the size of each of these whistling sounds can be confirmed in a set furnished with several kinds of volume control; increasing the volume before final detection the 5 intensity of the whistling will grow far more markedly than in direct proportion if they are due to terms of a high degree in the characteristics.

A way adapted to diminish the whistling according to the present invention consists in causing the change in frequency by the aid of a distinct detector constituted by a variable mu tube. It is known in the art (see the "Institute of Radio Engineers" for December, 1930, page 2102) that 10 the structure of the variable mu tube has as its object an attenuation in the development (1) of the terms of cV_g^3 , eV_g^5 ... resulting in cross-talk, or diaphony, if the tube does amplifier work; but the same structure further has this effect that 15 it reduces the terms of dV_g^4 , fV_g^6 ... which are responsible for the whistling of superheterodynes. The use of a variable mu, screen grid type tube as the first detector in a superheterodyne set will thus be efficient and suitable from this viewpoint. 20

25 In the case of frequency change insured by a radio modulator twin-grid tube in which case a control grid modulates an oscillation created by coupling between the plate, another grid and an oscillation circuit, exactly similar actions are 30 producible.

During oscillation the plate current as a matter of fact may be expressed thus:

$$(3) i = A + B \sin \omega t + C \sin 2\omega t + D \sin 3\omega t \dots$$

A, B, C, D ... being functions of the control grid 35 potential whose form depends further upon the impedances of the various circuits used in association with the twin grid tube and being thus expressible:

$$(4) \begin{aligned} A &= a_0 + b_0 V_g + c_0 V_g^2 + d_0 V_g^3 + \dots \\ B &= a_1 + b_1 V_g + c_1 V_g^2 + d_1 V_g^3 + \dots \\ C &= a_2 + b_2 V_g + c_2 V_g^2 + d_2 V_g^3 + \dots \end{aligned}$$

Referring to equation (3), what has been 45 neglected are the phases of the various harmonics or overtones of the oscillation for they are of no importance in this connection.

ω is the pulsation of the heterodyne; if, then, a 50 station with a pulsation ω_1 accompanied by jamming or interfering waves ω_2 , ω_3 , etc., is received it will have to be kept in mind that V_g comprises not only terms $\alpha \sin \omega_1 t$, $\beta \sin \omega_2 t$, $\gamma \sin \omega_3 t$, etc., but also a very substantial term $\eta \sin \omega t$ due to 55 the heterodyne current which, by virtue of inter-electrode capacitance returns to the impedance acting upon the control grid.

The term $b_1 V_g$ which by the intermediary of B, and multiplied by $\sin \omega t$ is introduced in i , then results in the change in frequency by control of the oscillation of the twin-grid tube in accordance with the well known process as explained by its inventors (Nozieres, Scott-Taggart, de Mare, and others). But it will be noted that the term $c_0 V_g^2$ will also produce the mean frequency as a result of simple detection as in a standard detector with separate heterodyne. Finally, in A, B, C, a great number of terms of a high degree of V_g will further produce, either as a result of interference between themselves or with the overtones of the oscillator, terms of mean frequency which most frequently will be associated with doubled, tripled, etc. modulation depth, and thus be extremely distorted. Finally, in the case where interfering stations, or waves, are received there will arise an entire gamut of 75

beats, in fact, an idea regarding the actual situation can be obtained on basis of the (by the way rather incomplete) list hereinabove given for the case comprising the Daventry, Radio-Paris and Eiffel Tower stations, whence there result, after a 5 certain number thereof have been fed into the mean frequency amplifier, various whistling actions which are themselves modulated.

The chief ways and means to be adopted with a view to avoid these troublesome effects are 10 the following, arranged in the order of diminishing effectiveness:

(1) To reduce as far as feasible the force of the signal at the instant of change of frequency in the radio modulator twin-grid tube, while 15 insuring sufficient protection against stray.

(2) Reduce in the developments A, B, C, the size of the terms d_0 , etc. . . . c_1 , d_1 , etc., and b_2 , c_2 , d_2 , etc.

(3) Reduce in the oscillation of the twin grid 20 tube the amplitudes of the harmonics.

(4) Lessen or eliminate completely the terms with $\eta \sin \omega t$ which occurs in the expression for V_g .

Now, the present invention discloses ways and 25 means adapted to realize each of these various points and the arrangements suggested with that end in view offer additional advantages some of which shall be hereinafter cited. The means and ways hereinafter to be described may be adopted 30 and used simultaneously (combinedly), or else singly and independently of one another according to the nature of the case and the difficulties to be solved.

In order to overcome the first condition herein- 35 before mentioned the invention discloses the simultaneous use of a radio frequency filter designed to lessen as far as feasible the stray compared with the signal, and an arrangement acting upon the control grid by the output of this filter, 40 though in combination with coupling means making the regulation of the radio frequency circuits practically independent of the regulation of the heterodyne.

In order to realize the second condition, the 45 invention suggests the construction and utilization of a twin-grid tube of a special kind where the control action exercised by the control grid is of what has become known as the "variable mu" kind.

In order to satisfy the third condition it is 50 necessary to insure careful regulation of the oscillation to a point very close to the point where it will be maintained; but the special design of twin-grid tube suggested to satisfy demand (2) 55 will be helpful also in satisfying condition (3).

The fourth condition is satisfied according to the invention either by the aid of neutrodyning, or by satisfying by way of choosing a special construction for the twin-grid tube and the oscillator, and further by the addition of small capacitors, a condition that shall hereinafter be indicated.

The invention will be better understood by reference to the drawings attached to this specification and the description in connection therewith giving merely by way of example several modes or embodiments of the basic ideas of the invention.

In the accompanying drawings the various circuit elements are designated by the customary symbols used for condensers, inductance coils, resistances, etc., as well known by the man trained in the art. To simplify the description details will be given only where needed. Moreover, tubes 70

75

comprising a plurality of electrodes are schematically indicated only by single electrodes, the filament being shown by a solid line, the grids by a broken line, plates by a rectangle, the screen grids being shown as surrounding the plates.

As regards the first condition it must be noted that the most conventional showing of the radio modulator twin-grid tube is as shown in Fig. 1. In this circuit scheme the tuned condition of the 10 coil, or loop, L by capacity C depends, due to the capacities between the grids C' , C'' and grid C'' and the plate, upon the tuning of the heterodyne circuit comprising the capacity C_1 . This circumstance has so far precluded a chance to act upon 15 the twin-grid tube by more than one tuned circuit for, in the circuit scheme shown in Fig. 2, for instance, owing to the presence of stray capacities due to grids c' , c'' , the adjustment of capacity C_3 is by no means the same as that of 20 the capacity C_2 , and this precludes all attempts at a simple regulation of the set and all chances of uni-control.

Fig. 3, by way of example, shows a method of coupling according to the invention which contrasted with the conventional arrangement shown in Fig. 1 increases selectivity, reduces the amplitude of the signal at the instant of frequency change, while insuring simple uni-control of the different capacities such as C_2 and C_3 . This end 30 is attained by coupling the filter L_2 , C_2 , L_3 , C_3 with the control grid by the aid of a potentiometer arrangement R_1 , R_2 . R_2 is the leak resistance of the grid, and the same is of an order of magnitude of 1 megohm. R_1 should be chosen sufficiently 35 high in order that the shunt constituted, for instance, by the capacity between the cathode and grid c' in series with C_1L_1 will not disturb the regulation of the circuit L_3 , C_3 . R_1 , on the other hand, should yet be made sufficiently small in 40 order that an appreciable potential across the terminals of L_3 should be transferred and fed to the control grid. With the usual twin-grid tubes and within the range of radio broadcasting it is found that $R_1=40,000\omega$ is a size adapted 45 to insure the desired results.

Referring to Fig. 3, r represents a capacity serving to couple the two tuned circuits L_2 , C_2 and L_3 , C_3 . Z stands for the mean-frequency filter which is provided at the output end of the 50 twin-grid tube.

Fig. 4 shows a modification wherein the two circuits (for instance) that constitute the filter are coupled by the mutual inductance M between the coils L_2 , L_3 of the resonant input circuits, the 55 upper end of coil L_3 being connected to the signal control grid through a high resistance R_1 , as in Fig. 3. Since the lower end of L_3 is grounded, R_1 serves also as a grid leak and R_2 is useless in this arrangement.

Fig. 5 shows a modification where one screen type tube L serves as an aperiodic coupling according to the invention, the resistance R_1 consisting then of the very high internal resistance of this tube. In such a scheme it is necessary 60 that the tube L should be carefully connected and polarized in order that no cross-talking may be occasioned; and with that end in view a variable mu tube is appropriate. As shown, the plate of tube L is resistance coupled by the condenser r to the signal control grid of the oscillator-detector tube, the control grid of which is provided with the leakage resistor R_2 . Fig. 6 shows another modification which will be self-understood and where the use of the resistance R_1 according to the invention makes it possible to 70

practice uni-control of capacities C_2 , C_3 . In this case, instead of the resonant circuits being inductively coupled together, the selectivity is secured by connecting one, including the condenser C_2 , in the control grid circuit and the other, including the condenser C_3 in the plate circuit of the tube, the plate being connected to the control grid of the detector tube through the series connection of condenser γ and resistor R_1 .

In Figs. 3 to 6 the radio frequency filter is constituted by only two tuned circuits, though it will be clearly understood that it is possible to provide a greater number of circuits, indeed, as many as may be needed. It should also be noted that the method of this invention insuring uni-control of C_2 , C_3 by perfect balancing out by the aid of C_1 allows of uni-control also of all of the variable condensers of the superheterodyne C_2 , C_3 and C_1 , for instance, by using the methods disclosed in French Patent No. 727,054, filed on January 30, 1931, entitled "Improvements in means insuring uni-control of several circuits tuned to dissimilar frequencies".

What should also be emphasized is the fact that the means here disclosed makes it readily feasible, without impairing quality to produce a diminution of the intensity of the signal at the time of changing the frequency. As a matter of fact it is generally deemed desirable to preserve the signal at a certain prior amplitude in order that, at the time when the frequency-change takes place, it may exceed the noise level known as the "twin-grid blast".

Now, the applicant believes to have ascertained that, save in the very exceptional instance of twin-grid tubes of poor quality, the said typical noise was nothing else but the fundamental noise due to the various and very extensive modulations of a great number of beats the origin of which has been hereinbefore demonstrated, so that every improvement in selectivity at radio frequency would manifest itself by a large increase in the ratio between signal and noise, even in cases where the signal is effectively reduced.

The invention further furnishes ways and means so as to insure simultaneously a more or less adequate fulfillment of the second and the third condition hereinbefore mentioned.

With this end in view it suggests the construction of twin-grid tubes with accelerator grid (contra-distinct from screen grid twin-grid tubes) involving the properties of variable mu in reference to the control grid, such variable mu feature being obtained by ways and means entirely similar to those nowadays known in regard to screen grid tubes. It further discloses the use of such twin-grid tubes comprising an accelerator grid and the variable mu feature for radio modulator twin-grid tubes for insuring frequency change. In the case of an autodyne circuit scheme, also according to the invention, it is possible to use for the autodyne tube a variable mu screen grid tube.

In Figs. 7A, 7B by inclining the electrode relative to the vertical the method whereby the tube is made of variable mu has been indicated schematically by modification of the construction of the said electrode, though it will be understood that also such other methods like a simple shift of the grid, variable spacing of the grid wires, etc., resulting in variable mu could just as well be employed.

Referring to Fig. 7A, if g_2 is the control grid, the tube is of variable mu according to the sense of this invention; but if g_1 is the control grid, 75

it will be understood that this will not be so and that the plate current i_p expressed as a function of V_g will comprise terms of a high order with substantial coefficients for $V_g 1$ and far lower ones for $V_g 2$. In Fig. 7B there will be seen a twin-grid tube which involves the variable mu feature for both $g1$ as well as $g2$. In both illustrations just referred to C designates the cathode and P the plate.

10 Fig. 8 shows the characteristics of such a twin-grid tube. There are shown by the solid lines the curves of the plate current and of the current of the first grid $g1$, for a certain potential applied to these two electrodes, as a function of 15 the potential of the control grid $V_g 2$. These characteristics present a very regular curvature, while the characteristics traced by broken lines of the ordinary twin-grid tube present rectilinear portions throughout a wide range of variation of $V_g 2$.

10 The following effects result, to wit: The standard twin-grid tube as soon as it starts to oscillate, oscillates at a large amplitude, the variable mu twin-grid tube oscillates with a smaller amplitude 25 and a lower number of harmonics. This effect will be more conspicuous if the said twin-grid tube with the variable mu feature has been designed with a rather "slack" grid pitch and is operated on a low plate potential.

30 On the other hand, in Equations (4) the functions of A, B, C, no longer contain terms of V_g of a high order and of substantial amplitude, and this always as a result of the variable mu property. The stray whistling noises are thus greatly 35 diminished for this two-fold reason, namely, that the construction intended to insure variable mu satisfies requirements and that in the following equation for V_g

$$(5) \quad V_g = \alpha \sin \omega_1 t + \rho \sin \omega_2 t \dots \lambda \sin \omega t$$

40 the very important term $\lambda \sin \omega t$ has been greatly diminished, the variable mu twin-grid tube oscillating less strongly. It is true that this effect manifests itself also in the form of a substantial reduction in sensitiveness; but it will be preferable to put up with this loss in order to insure a proper frequency-change process.

45 In the following shall be disclosed the method of this invention with a view to cause the practical disappearance of the term $\lambda \sin \omega t$ in equation V_g ; as a result there is caused the disappearance 50 in the plate current of a large number of beats wherein the said term occurs in the form of a component.

55 Fig. 9 illustrates in a sufficiently evident way the means adapted to neutralize perfectly the capacities $c' c''$ by similar (or proportional) capacities according to whether the windings $L1, L2$ are divided into equal (or proportional) parts. As 60 shown, the top of winding $L1$ is connected to the oscillator grid, the lower portion of this winding and condenser C' providing a circuit to neutralize the capacity effect between the two grids. The plate output circuit is connected to a midpoint 65 of the coil $L2$, whereby it is possible to neutralize the capacity between the plate and outer grid by connecting the lower end of $L2$ to this grid through the condenser C'' .

70 Fig. 10 shows a neutralizing arrangement that is far simpler, but efficient only if the oscillator of the twin-grid tube is coupled very closely. In this instance it is possible to show that if $\alpha \sin \omega t$ is the expression of the signal that would be impressed upon the control grid $g2$ in the absence 75 of all capacities c' and c'' , the reaction in the

twin-grid tube due to c' and c'' has the result of imparting to $V_g 2$ the following values, to wit:

$$(6) \quad V_g 2 = \frac{\alpha \sin \omega_1 t + Z(\omega)(jc' \omega \frac{M}{L} + jc'' \omega) V_p}{1 + Z(\omega)(jc' \omega + jc'' \omega)}$$

10 $V_p = V_{p0} \sin \omega t$ is the oscillating part of the plate potential, $Z(\omega)$ is the impedance encountered by the heterodyne wave ω between the control grid and the filament return, expression (6) being valid only if the oscillator is coupled strongly.

A perfect neutralizing for all frequencies is then obtained if this condition is fulfilled, to wit:

$$\frac{c''}{c'} = -\frac{M}{L} (M < 0) \quad 15$$

and this will always be practicable by an appropriate construction either of the twin-grid tube for a given oscillator or of the oscillator for a given twin-grid tube or else again by the proper setting of the small variable condensers.

Finally, the calculation that resulted in Equation (6) suggests a novel means that has been proved effective by practical experience, namely, of securing a very pure medium-frequency detection by using a circuit scheme of the kind shown in Fig. 11.

In this arrangement the twin-grid tube B is mounted and connected like an ordinary radio modulator twin-grid tube, but it is employed 30 merely for producing the sum of voltages $\alpha \sin \omega_1 t + \lambda \sin \omega t$ in Equation (5) which here assumes the shape of Equation (6), the said aggregate potential being applied to the grid of the detector tube of mean frequency E which preferably should be a variable mu tube resulting in extremely pure detection of median frequency. As shown, the signal frequency is applied to the outer grid of tube B through the resistor $R1$, the oscillation frequency being generated by the 40 feedback coupling between the plate circuit and the resonant circuit connected to the inner grid. The sum of the signal and oscillation frequencies is transferred from the signal grid of B to the control grid of the detector tube E by directly 45 connecting these grids, as shown.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

55 What is claimed is:

1. In combination in a superheterodyne receiver, an energy collecting means, a vacuum tube detector having a cathode, grid and plate, said grid being arranged to provide a variable mu plate current characteristic, two coupled circuits connected in cascade and each tunable to the incoming signal frequency, one of said circuits being coupled to the energy collecting means and an aperiodic circuit conductive to direct current connected to the second of said tunable circuits 65 and to the grid of said tube.

2. In a superheterodyne receiver, the combination of a vacuum tube having a cathode, a control grid, a second grid and a plate, a circuit tunable over a range of signal frequencies connected to 70 the control grid and cathode, said circuit comprising a plurality of similar tuned circuits and an aperiodic coupling between the last of said circuits and said control grid, a circuit tunable to a desired oscillation frequency connected to the 75

- second grid and cathode, a plate circuit having a feedback connection to said last named circuit, the control grid being so constructed and arranged as to provide a variable mu characteristic 5 to the current between the cathode and said second grid.
3. In a superheterodyne receiver, the combination of a vacuum tube detector having a cathode, a control grid, a second grid and a plate, a circuit 10 tunable to a desired oscillation frequency connected between the second grid and cathode, a plate circuit having a feedback connection to said circuit, said second grid being so arranged with reference to said plate as to provide a vari- 15 able mu plate current characteristic, means for neutralizing the capacity between the control grid and plate, a source of signal frequency energy and means connecting said source to the cathode and control grid, comprising two coupled 20 circuits each having means for tuning it to the incoming signal frequency, and an aperiodic coupling between one of said coupled circuits and the control grid.
4. In combination in a superheterodyne receiver, a source of high frequency energy, a vacuum tube oscillator having a control grid, a second grid and a plate circuit, a feedback connection between the plate circuit and the second grid, a detector tube having a control grid, a 25 screen grid and a plate circuit said control grid being constructed to provide a variable mu plate current characteristic, means connecting a positive source of potential to the screen grid, a circuit tuned to the intermediate frequency connected 30 in said plate circuit, a connection conductive to direct current between the control grids of the tubes and an aperiodic coupling means connecting one of said control grids to the said source of energy.
- 40 5. In a superheterodyne receiver, the combination of a vacuum tube detector having a cathode, a control grid, a second grid and a plate, a circuit tunable to a desired oscillation frequency connected between the second grid and cathode, a plate circuit having a feedback connection to said circuit, a source of signal frequency energy, means for coupling said source to the cathode and control grid, said means comprising a plurality of similar resonant coupled circuits each 45 tuned to the signal frequency and an aperiodic coupling means connecting the last of said circuits to said control grid, said control grid and said second grid being constructed and arranged to provide a variable mu plate current character- 50 istic.
- 55 6. In a superheterodyne receiver, the combination of a vacuum tube detector having a cathode, a control grid, a second grid and a plate, a circuit tunable to a desired oscillation frequency connected between the second grid and cathode, a plate circuit having a feedback connection to said circuit, a source of signal frequency energy, means coupling said source to the cathode and control grid, said second grid being 55 constructed and arranged to provide a variable mu plate current characteristic whereby said tunable circuit is substantially free of harmonic frequencies of its oscillation frequency.
7. In a superheterodyne receiver, the combination of a vacuum tube having a cathode, a control grid, a second grid and a plate, an input circuit connected to said cathode and control grid, means for impressing radio frequency signal currents on said input circuit, a circuit tunable to a desired local oscillation frequency connected 15 between the second grid and cathode, a plate circuit having a feedback connection to said tunable circuit, said control grid and said second grid being disposed in oppositely inclined planes with 20 reference to said plate.
8. In a radio receiver, the combination of a vacuum tube detector having a cathode, a control grid, a second grid and a plate, a circuit tunable to a desired oscillation frequency connected 25 between the second grid and cathode, a plate circuit having a feedback connection to said circuit, a source of signal frequency energy, coupling means arranged to connect said source to said control grid, said second grid being inclined 30 at an acute angle with reference to said plate so as to provide a variable mu plate current character- 35 istic.
9. A superheterodyne receiver comprising the combination of a vacuum tube oscillator-detector having a cathode, a control grid and two additional cold electrodes, a circuit tuned to a desired oscillation frequency connected to one of said cold electrodes, a circuit connected to the other of said cold electrodes including a portion 40 having a feedback connection to said tuned circuit, a source of signal frequency energy and a circuit coupling said source to said control grid and including a portion resonant to the incoming signal frequency, said control grid being constructed of wire having a variable spacing between its adjacent portions whereby to provide 45 a variable mu plate current characteristic.
- 50
